UNITED STATES PATENT OFFICE.

LOUIS H. THULLEN, OF UPPER MONTCLAIR, NEW JERSEY.

SWITCH OPERATING AND LOCKING DEVICE.

Application filed February 24, 1926. Serial No. 90,274.

This invention relates to devices for operating and locking switching apparatus, and more particularly to such devices for use in connection with high tension outdoor switch 5 structures.

In operating high tension switching apparatus for convenience and safety of the operator, it is desirable that the operating handles be located at a point remote from the 10 region of the dangerous area around the switch parts which are charged to a high potential. The locking and unlocking and other control operations should also be preferably accomplished without the necessity of 15 the operator's coming in contact with any of the metallic operating parts of the apparatus even though such parts are normally insulated from the high potential line.

In view of the above facts, I have found 20 it to be desirable in accordance with this invention to provide the novel form of switch operating and locking means hereinafter described at a point spaced a substantial distance from the other switch apparatus and 25 associated with such apparatus merely by an insulating operating rod. My improved locking lever device may however be applied to other arrangements and uses.

The main object of the invention is to provide 30 an efficient switch operating device of the type above indicated, by which the switch lever may be locked in either its closed or its open position, and which is provided with means tending to prevent its unauthorized or 35 accidental shifting from one position to the other.

Further and more specific objects, features 40 and advantages will more clearly appear from the detail description given below taken in connection with the accompanying drawings which form a part of this specification. In the accompanying drawings—

Fig. 1 is an elevational view of a preferred embodiment of the invention as associated 45 with suitable switching apparatus.

Fig. 2 is a longitudinal sectional view showing in detail the parts of the locking device and operating handle embodying the invention.

Fig. 3 is a longitudinal sectional view taken 50 at right angles to the sectional view of Fig. 2.

Fig. 4 is a sectional view taken substantially 55 along the line 4—4 of Fig. 2 and showing an end view of the operating handle embodying this invention in one of its phases.

Fig. 5 is a sectional view taken substantial-

ly along the line 5—5 of Fig. 2 and illustrating an end view of the locking means embodying this invention.

Referring to the drawings in further detail and particularly to Fig. 1, switch arms 10 and 11 are illustrated as being fixed on rocking insulator supports 12 and 13 respectively, the insulator supports being rocked by an insulating operating rod 14 pivotally connected to a crank arm 15. The crank arm in turn serves to control a rockable supporting fixture of any suitable type at 16. The fixture 16 is operatively associated with a corresponding rockable supporting fixture 17 through a connecting link member 18. When the operating rod 14 is thrown to its extreme upward position, the switch arms 10 and 11 are moved to the closed circuit position and when the operating rod 14 is drawn 75 downwardly, the switch arms are thrown to their open circuit position.

An operating lever 19 is pivotally mounted at a fixed point 20 and is pivotally connected at 21 to the operating rod 14. A suitable fixed clamping device 22 may be provided such as in the form of a quadrant or other arcuate form. The assembled locking mechanism is indicated at 23 at the end of the lever 19 opposite from the pivotal connection 21. An insulating handle member 24 is designed to be detachably connected to the locking mechanism 23 in a manner herein-after described. The handle member 24 may preferably be formed with a D shaped grip portion 25, which will permit the handle to be readily turned or moved in and out and up and down as desired.

Referring to Figures 2 to 5 the locking mechanism 23 will now be described in further detail. The quadrant member 22 is provided with notches 26 and 27 respectively for engaging the locking means when the switch is in its closed and open circuit positions. The lever 19 is encircled by a sleeve member 28 which is shaped to normally engage the recesses or notches 26 and 27. The lever member 19 is provided with a slot or aperture 29 through which the quadrant member 22 freely slides except when engaged by the sleeve member 28. The edge of the sleeve member 28 adjacent the quadrant 22 may be provided with a pair of oppositely disposed notches as at 30 and 31 whereby when the sleeve is turned to the proper position with respect to the lever 19, the quadrant member 22 will pass through the notches 30 and 31.

thus permitting the lever 19 to freely slide over the quadrant member.

However, the sleeve member 28 is normally retained in a position as shown in Fig. 2 where it engages the quadrant member and locks the lever and switch apparatus against movement. To retain the sleeve member in this locked condition a pair of spring pressed dog members 32 and 33 may be pivoted with in suitable recesses formed in the lever member 19. Small coil springs 34 and 35 lodged within the recesses serve to press the ends 36 and 37 of the dog members 32 and 33 respectively into engagement with recesses 38 and 39 formed in the sleeve 28. Until the dog members are retracted the sleeve member 28 is thereby held against rotation or other movement on the lever member 19.

The handle member 24 may comprise a rod of wood or other insulated material provided with a hollow ferrule member 40 which also acts as a key member in unlocking the locking device above described. The ferrule member 40 is of such diameter as to fit upon the end of the lever member 19 and to readily slide thereover. When the ferrule member is slid in position on the lever 19 portions 41 and 42 of the dog members 32 and 33 respectively are forced inwardly, which operation affects the release of the portions 36 and 37 and permits the sleeve member 28 to be thereafter rotated. The ferrule member 40 may also be provided with suitable lugs or key portions as at 44 and 45 for engaging corresponding recesses as at 46 formed in the edge of the sleeve 28. After the end of the handle member 24 has been applied and the key portions 44 and 45 are in engagement with the sleeve 28, the grip portion 25 of the handle may be rotated through an angle of 90° by the operator which rotation will cause the sleeve notches 30 and 31 to be brought into alignment with the quadrant member 22 and into a position in which they straddle the quadrant member 22. Thereupon the operator may raise or lower the lever 19 about its pivoting point 20 to close or open the switch.

The lever 19 may be provided with retaining screws as at 47 (see Fig. 2) and as at 48 (see Fig. 3). These retaining screws are received in suitable slots 49 and 50 respectively, which slots extend longitudinally of the handle member 24. At the inner ends of the slots 49 and 50 transverse slot extensions 51 and 52 respectively may be provided, which extensions receive the retaining screws or pins 47 and 48 at such times as the operating handle is turned to rotate the sleeve 28 to unlocked position. The retaining screws being received within these transverse slots, the operating handle at such times cannot be removed from the locking device. The operator is, therefore, prevented from removing the handle and leaving the lever 19 in un-

locked condition. However, as soon as the device is restored to locked condition by turning the sleeve 28 back through an angle of 90° the retaining screws 47 and 48 are brought back into the slots 49 and 50 and the handle may then be removed. When the handle is removed, the coil springs 34 and 35 will again be free to force the dog end portions 36 and 37 outwardly and thus again securing the sleeve 28 in locked condition in a position in which it locks the lever 19 with respect to the quadrant 22. The dog members may be secured within the lever member 19 by means of a transversely extending pivoting pin 53 located at the point where the dog members 32 and 33 intersect and cross.

While I have described my improvements in great detail and in connection with a preferred form thereof, I do not desire to be limited to such details or form since many changes and modifications may be made and the improvements embodied in widely different forms without departing from the spirit and scope of the invention in its broader aspects. Therefore, I desire to cover all modifications and forms coming within the language or scope of any one or more of the appended claims.

What I claim as new and desire to secure by Letters Patent is:

1. A device for actuating and locking high tension electrical apparatus or the like against movement comprising a pivotally mounted lever, means operatively connecting said lever to the electrical apparatus, an arcuate frame member slidably engaged by said lever, locking means on said lever and notches formed in said frame member which coact to lock the lever and apparatus in either of two positions, a detachable insulated operating handle for said lever, and key means on said handle to unlock said locking means when the handle is applied and given a turning movement, and means acting to retain the handle against removal until the locking means is restored to locked condition.

2. A device for operating and locking electrical apparatus against unauthorized or accidental movement, comprising a pivotally mounted lever, means operatively connecting said lever to the apparatus, an arcuate frame member slidably engaged by said lever, locking means on said lever and notches formed in said frame member which coact to lock the lever and apparatus in either of two positions, a detachable operating handle for said lever, and key means on said handle to unlock said locking means when the handle is applied and given a turning movement.

3. A device for operating and locking levers comprising an operating lever, an arcuate frame member slidably engaged by said lever, locking means on said lever and notches formed in said frame member which coact to lock the lever in either of two posi-

tions, said locking means comprising a sleeve encircling the lever and shaped to engage said notches in the arcuate frame member when turned in one position and to permit the lever 5 to freely slide over the arcuate frame member when said sleeve is turned in another position on the lever and electrically insulated means with a grip portion widely spaced from the locking means for controlling the position of 10 said sleeve.

4. A device for operating and locking levers comprising an operating lever, an arcuate frame member slidably engaged by said lever, locking means on said lever and notches 15 formed in said frame member which coact to lock the lever in either of two positions, said locking means comprising a sleeve encircling the lever and shaped to engage said notches in the arcuate frame member when 20 turned in one position and to permit the lever to freely slide over the arcuate frame member when said sleeve is turned in another position on the lever, and spring pressed means normally retaining said sleeve against turning 25 and in engagement with said notches and electrically insulated means with a grip portion widely spaced from the locking means for controlling the position of said sleeve.

5. A device for operating and locking 30 electrical apparatus against unauthorized or accidental movement, comprising a pivotally mounted lever, means operatively connecting said lever to the electrical apparatus, an arcuate frame member slidably engaged by 35 said lever, locking means on said lever and notches formed in said frame member which coact to lock the lever and apparatus in either of two positions, said locking means compris-

ing a sleeve encircling the lever and shaped to engage said notches in the arcuate frame 40 member when turned in one position and to permit the lever to freely slide over the arcuate frame member when said sleeve is turned in another position on the lever, spring pressed means normally retaining said sleeve 45 against turning and in engagement with said notches, and a detachable lever operating handle provided with key means for releasing said spring pressed means and for turning said sleeve out of engagement with the 50 notches.

6. A device for operating and locking control levers of electrical apparatus comprising a lever, an arcuate frame member slidably engaged by said lever, locking means on said 55 lever and notches formed in said frame member which coact to lock the lever, said locking means comprising a sleeve encircling the lever and shaped to engage said notches in the arcuate frame member when turned in 60 one position and to permit the lever to freely slide over the arcuate frame member when said sleeve is turned in another position on the lever, spring pressed means normally retaining 65 said sleeve against turning and in engagement with said notches, and a detachable insulated operating handle provided with key means for releasing said spring pressed means and for turning said sleeve out of engagement with the notches, and 70 means acting to retain the handle against removal until the locking means is restored to locked condition.

In testimony whereof I have signed my name to this specification.

LOUIS H. THULLEN.
